Primary Examiner — John Windmuller*Assistant Examiner* — Steven Czyz(57) **CLAIM**

I claim the ornamental design for a congratulatory device, as shown and described.

DESCRIPTION

FIG. 1 is a front view of the congratulatory device.

FIG. 2 is a rear view of the claimed design.

FIG. 3 is a left side view of the claimed design.

FIG. 4 is a right view of the claimed design.

FIG. 5 is a top view of the claimed design.

FIG. 6 is a bottom view of the claimed design; and,

FIG. 7 is a perspective view of the claimed design.

FIGS. 1 and 7 include the word "LOGO" in broken lines, which is environmental matter forming no part of the claimed design.
